DESIGN FOR A LADY'S UNDERGARMENT

Helen A. Laufer, New Kensington, Pa.

Application November 10, 1939, Serial No. 88,196

Term of patent 3½ years

To all whom it may concern:

Be it known that I, Helen A. Laufer, a citizen of the United States, residing at New Kensington, in the county of Westmoreland and State of Pennsylvania, have invented a new, original, and ornamental Design for Lady's Undergarment, of which the following is a specification, reference being had to the accompanying drawing, forming part thereof.

I claim:

The ornamental design for a lady's undergarment, as shown.

HELEN A. LAUFER.
